Inventor,

John S. Dunlap

per A. B. Upham,
attorney in fact.

UNITED STATES PATENT OFFICE.

JOHN S. DUNLAP, OF PEORIA, ILLINOIS.

STOOL-SEAT.

SPECIFICATION forming part of Letters Patent No. 292,211, dated January 22, 1884.

Application filed September 29, 1883. (No model.)

To all whom it may concern:

Be it known that I, JOHN S. DUNLAP, of Peoria, in the county of Peoria, in the State of Illinois, have invented an Improved Stool-Seat; and I do hereby declare that the following is a full, clear, and exact description thereof, reference being had to the annexed drawings, making a part of this specification, in which like letters of reference refer to like parts, and in which—

Figure 1 represents a vertical section of the invention through the center; Fig. 2, a side elevation with part of ring broken away; Figs. 3, 4, 5, sections of modifications; Figs. 6, 7, and 8, plans of modified forms.

The object of this invention is the construction of means which, while serving to secure easily and strongly the upholstering upon a stool or similar article of furniture, forms also an ornamental binding for the same.

In the drawings, A is the foundation-board, upon which the upholstering is laid, and which is, in the stool shown, made circular in form, but having its edge chamfered, as shown in Fig. 1.

D is the stuffing of the seat, and B is the covering of the same.

C is a metal ring, made to fit about the board A, and having its upper diameter slightly shorter than its lower one. This ring C, I usually make of cast metal plated, japanned, or otherwise made ornamental in appearance.

In forming the seat of this stool the stuffing or cushion is first secured upon the board A, the covering B cut the right shape and size and put on over the same. The ring C is then pressed down over the edge of the covering and down the side of the board A until the upper edge of the ring C enters the groove A', made in the side of said board A, as shown in

Fig. 2. The ring C is made thin and slightly smaller than the board A, so that it could only be impressed down past the upper edge of the board A and into its groove A' by the application of some little force and by the elasticity of said ring C. By this means, when the ring is once pressed home, it retains itself in place without other fastening. This downward impressing of the ring C serves to tighten and pull smoothly over the stool the covering B, which is gripped by the upper edge of said ring, pulled downward and held in the groove A' as the said upper edge of the ring C springs therein. The said covering fabric B may be tacked about the side of the board A, if desired; but I find that the ring alone is able to hold the upholstering in place.

I sometimes stitch a narrow strip of burlap or other thick fabric upon the edge of the covering B, to give the ring C better hold upon the same; but if the board A is well seasoned such a strip, B', is unnecessary.

What I claim as my invention is as follows, to wit:

As a seat for a stool or similar article of furniture, the circular foundation-board A, having its edge chamfered and provided with the groove A', as shown and described, in combination with a covering, B, of fabric or similar material, and the thin metal ring C, contracted in diameter at its upper edge, substantially as and for the purpose specified.

In testimony that I claim the foregoing invention I have hereunto set my hand this 27th day of September, 1883.

JOHN S. DUNLAP.
